UNITED STATES PATENT OFFICE.

HARRY CHARLES RIDOUT, OF BOURNEMOUTH, ENGLAND.

RESILIENT HEEL OR LIFT FOR BOOTS AND SHOES.

1,351,691.

Specification of Letters Patent. Patented Aug. 31, 1920.

Application filed January 7, 1920. Serial No. 349,915.

To all whom it may concern:

Be it known that I, HARRY CHARLES RIDOUT, a subject of the King of Great Britain, and residing at Bournemouth, Hampshire, England, have invented new and useful Improvements in Resilient Heels or Lifts for Boots and Shoes, of which the following is a specification.

This invention consists of improvements in and relating to resilient heels, or lifts, for boots and shoes; made from rubber, composition, or any other suitable material that can be used for the purpose and according to which in order to enable the resilient heel, or lift, (hereinafter referred to as a lift) to be attached to a boot or shoe (hereinafter referred to as a boot) in such an improved manner that a more perfect attachment and closeness of fit than has hitherto been possible is obtained and maintained between it and the boot, both before and after considerable wear of the lift has taken place.

One of the objects of the present invention is to provide a lift so formed and in which suitable metal washers or their equivalent is incorporated whereby when the affixing devices for holding the lift are placed securely in position in the boot, the change brought about thereby to the original molded configuration of the lift is such that acting in conjunction with the resilient material from which it is made, insures that portion forming its center, and also its marginal edge or flange, permanently to exercise (particularly from such marginal edge and the centrally placed domed-part) an abnormal resilient pressure or effort on the undersurface of a boot to which it is attached, said resilient effort being in addition to, but quite independent of, the more intense closeness of attachment derived from vacuum chambers provided as auxiliary devices.

In order that the invention may be clearly understood it will hereinafter be described with reference to the accompanying drawings, in which:

Figure 1 is an upper-face plan of one form of the improved lift.

Fig. 2 is a sectional view taken on the line 2—2 of Fig. 1.

Fig. 3 is an end view showing the breast end of the lift shown in Fig. 1, but with tiers on its under face.

Fig. 4 is an under-face plan of one form of the improved lift.

Fig. 5 is an end view showing the breast end of the lift shown in Fig. 4.

Fig. 6 is an edge view to an enlarged scale, of a perforated curled and dished washer of the kind used in this invention.

Fig. 7 is a sectional view taken on the line 7—7 of Fig. 8, shown in edge view in Fig. 6 also, of the washer.

Fig. 8 is a plan view of the washer shown in Fig. 6.

Fig. 9 is a view of a lift of the kind shown in Figs. 1 to 5, after application and affixing to a boot heel.

Figs. 10 and 11 show, to an enlarged scale, two different forms of nails of the kind used according to this invention for securing such lifts to a boot.

Fig. 12 is an upper face plan of a round form of the improved lift.

Fig. 13 is a sectional view taken on the line 13—13 of Fig. 12.

Fig. 14 is a view of a lift of the kind shown in Fig. 12 after application and affixing to a boot heel; the same lift of an enlarged or reduced size may be applied as pads to a boot sole.

Fig. 15 is a plan view of a perforated, curled and dished washer of the kind used in the form of lift shown in Fig. 12.

Fig. 16 is a sectional view taken on the line 16—16 of Fig. 15.

Fig. 17 is an under face plan of a lift of the kind used in one form of this invention in which a complete covering for the sole of a boot after application and affixing thereto is shown.

Fig. 18 is an under face plan of three toe or heel pads or lifts, according to this invention, after application and affixing in

one of many methods of placement on the sole of a boot.

Like letters of reference indicate like parts throughout the drawings, in which:—

- 5 According to the present invention the lift (a) (measured from its undere marginal edge and for a distance therefrom toward its center on its under face) is formed so as to have a convex or curved-flange or part (e) blending into a concavity (g) centrally placed therein; and (measured from its upper marginal edge and for a distance therefrom toward its center on its upper or attaching face) said lift (a) is 10 formed so as to have a concave or curved-flange or part (b) terminating where one 15 row of a number of tiers or steps (c) are provided and placed approximately concentric or parallel to said upper marginal edge 20 of the lift (a) in which tiers or steps (c) are located centrally thereto in a convex or domed-part (d²), or in either or both (and to increase and intensify the vacuum area 25 essential during application and before any securing devices are employed), there are provided a number of auxiliary concavities (d¹) and (c¹) whereby when the resilient lift (a) is pressed against the flat or under surface of a boot, air is expelled and a partial 30 vacuum results in all the auxiliary concavities (d¹) and (c¹), in addition to that vacuum operating in the larger hollowed form (see Figs. 2 and 13) consisting of the concaved flange-part (b) and the further 35 depression formed by the placement of the tiers or steps (c) hereinbefore referred to.
- 30 The acting or upper faces of the steps or tiers (c) are constructed, during molding of the lift (a) parallel to the single plane 40 of the upper marginal continuous free edge 45 of said lift (a) but after depression of the lift (a) which arises during its affixing, said tiers (c) assume slight angularity thereto, and their edges present and offer (due to the 50 displacement of the material) extreme resilient effort when placed and pressed on a flattened surface thereby insuring for each edge on each row of steps or tiers (c) a perfect vacuum sealing.
- 50 A condition of partial vacuum is necessary to temporarily hold the resilient lift (a) in a flattened state and firmly in the desired position, the object being to allow the affixing nails, screws, or the like, to be truly 55 and correctly inserted in the boot, and to accomplish this effectually, the auxiliary concavities (c¹) in the tiers (c) and (d¹) in the domed part (d²) are provided for insuring better adhesion of the lift (a) during 60 affixing; especially if the surface of the boot is irregular, as each auxiliary concavity acts as a separate suction area quite independently of the large suction area formed by

the hollowed construction of the upper face of the lift (a), surrounded by the beveled, 65 concave, or curved-flange (b).

In practice it is found that the center of a lift has the greatest tendency to break contact with the surface of a boot both during and after application thereto, and to overcome this defect the lift (a) is provided with the convex domed-part (d²) containing auxiliary concavities (d¹) therein, said part (d²) being surrounded by a flat bottom-part (d) adjacent to the inner row of tiers (c). This 75 construction produces what may be described as a waved or corrugated form when viewed in cross-section, (see Figs. 2 and 13). To obtain this corrugated form in cross-section, which is necessary for successfully maintaining the lift (a) flat on a boot heel (H), or a sole (K), said lift (a) is formed on its under face with a convex or curved-flange (e), which may have a smooth surface, or, be provided with shallow or beveled tiers, 85 or steps (f), (see Fig. 3); in either case said flange (e) blends into a centrally placed concavity (g) provided and located on the opposite face to that occupied by the convex or domed-part (d²) and the flat part (d).

By producing a resilient heel, or lift (a) with an arrangement of steps or tiers (c) and of a corrugated-like form in cross-section, it gives the closest approximation to an equal thickness of the lift (a) at any part 95 when it is flattened out.

In order that a resilient lift (a) may be properly attached to a boot heel (H), or boot sole (K), it is necessary when nails are employed, that these should be hammered 100 down straight and truly through the lift (a) into the heel (H), or sole (K) of the boot, but due to the shortness of the nails suitable for attaching a lift (a) to a boot sole (K), it is difficult if possible to do so 105 while holding the nail for guidance, and if the nail is not held in an upright position before it is struck by the hammer, it is knocked sideways, and penetrates crookedly, or may not even penetrate at all.

In the present invention the lift (a) is constructed with small openings (h) of less diameter than the body of the affixing device employed, these openings (h) are provided for locating the affixing devices in a 115 position so that they enter the countersunk center and hole (i') of the curled-edged washers (i) incorporated in the lift (a). Said washers (i) are constructed with a dished or saucer-shaped body (i²) and are provided with said curled edge (i³) so as to prevent their edges cutting the resilient material from which the lift (a) is formed; said washers (i) are further provided with communicating perforations (i⁴) therethrough 120 for allowing jointure to be made through 125

said perforations by the resilient material composing the lift (a).

To be used as a combination with such resilient lifts, heels, or soles as hereinbefore referred to, openings (h) are formed with a conoidal enlargement (h¹), these are provided to accommodate the heads of the affixing nails (j) or the like. The nail (j) is either formed with an oval - countersunk head (j¹) or a countersunk head (j²) and is constructed to have emanating from either form of head in axial alinement with the body of the nail an extension-piece (j³), provided to facilitate the holding the nail for driving it in truly. On the extension-piece (j³) and close to the head of said nail a reduced part (j⁴) is provided, which enables the said extension-piece (j³) to be easily broken off from the nail head, after it has served the purpose of guiding the said nail during its insertion, and of further allowing the countersunk head - part to be driven firmly down into the countersunk center (i¹) of the washer (i). As the location of the washer (i) and nail head (j¹) or (j²) is considerably in from the under surface of the lift (a), it makes it necessary that a large amount of wear must occur to the under face of said lift (a) before the nail heads (j¹) or (j²) or the washer (i) could make wearing contact with anything; this condition would not obtain were the before-mentioned extension-piece (j³) not broken off.

It is obvious that when a punch is employed for driving a nail into flexible material, even should there be a guiding hole therein, said punch cannot control the direction of the nail, in fact, in practice a punch usually causes the nail to enter crookedly, and to obviate this defect in affixing lifts to boots the detachable extension-piece (j³) provided on the nail (j) hereinbefore described, has been designed to be used in combination with the lift (a) and washers (i).

Owing to the snug fit of the nails (j) and the location of the openings (h) in the lift (a), and to the auxiliary suction areas or concavities (c¹) and (d¹), the partial vacuum established during attachment and the closeness of fit between the lift (a) and the boot will not be impaired to any appreciable extent, more especially so when acting in conjunction with the important resilient condition resulting from the endeavor of the material to return to the waved or corrugated form of the lift (a) as originally molded and as shown in Figs. 2 and 13 in cross section.

When in their final position the securing nails (j) or the like and the washers (i) are wherever possible located in such a manner

as to draw the ridge portion (e) of the lift (a) perfectly flat.

It will be obvious that lifts for the heels of boots as shown in Figs. 1 to 5 or lifts for the heels of boots or circular pads for the soles of boots, but of different sizes, as illustrated in Figs. 12 to 14, or lifts for completely covering the soles of boots, as shown in Fig. 17, or lifts used as toe, sole, or heel pads, as shown in Fig. 18 may be constructed with various marginal forms and in the improved manner described hereinbefore without departing from the spirit of the invention.

What I claim is:—

1. In a resilient lift for boots, the combination of a plurality of surfaces arranged in tiers on the upper part of the lift so as to provide a plurality of recesses one within another in the upper face of the said lift.

2. In a resilient lift for boots, the combination of a plurality of surfaces arranged in tiers on the upper part of the lift so as to provide a plurality of recesses one within another in the upper face of the said lift the marginal edges of which are arranged in a single plane.

3. In a resilient lift for boots, the combination of a plurality of surfaces arranged in tiers on the upper part of the lift so as to provide a plurality of recesses with parallel upper surfaces arranged one within another in the upper face of the said lift the marginal edges of which are arranged in a single plane parallel to the upper faces of the several tiers.

4. In a resilient lift for boots, the combination of a plurality of surfaces arranged in tiers on the upper part of the lift so as to provide a plurality of recesses one within another in the upper face of the said lift and similar in contour to the marginal edges of the said lift.

5. In a resilient lift for boots, the combination of a plurality of surfaces arranged in tiers on the upper part of the lift so as to provide a plurality of recesses one within another in the upper face of the said lift, and a domed part extending upwardly within the innermost recess.

6. In a resilient lift for boots, the combination of a plurality of surfaces arranged in tiers on the upper part of the lift so as to provide a plurality of recesses one within another in the upper face of the said lift, and areas of depressed surface on the surfaces forming the said recesses.

7. In a resilient lift for boots, the combination of a plurality of surfaces arranged in tiers on the upper part of the lift so as to provide a plurality of recesses one within another in the upper face of the said lift, a domed part extending upwardly within the

innermost recess, and areas of depressed surface on the surface of said domed part.

8. In a resilient lift for boots, the combination of a plurality of surfaces arranged in 5 tiers on the upper part of the lift so as to provide a plurality of recesses one within another in the upper face of the said lift, and a convex surface forming the under face of the lift.

10 9. In a resilient lift for boots, the combination of a plurality of surfaces arranged in tiers on the upper part of the lift so as to provide a plurality of recesses one within another in the upper face of the said lift, a 15 convex surface forming the under face of

the lift, and a concave surface within the said convex surface.

10. The combination with a resilient lift for boots, of a washer, a nail passing through the said lift and washer to serve as 20 means for fastening the lift to a boot, and an extension of the said nail arranged so that it is readily removable by breakage.

Dated this seventeenth day of December, 1919.

HARRY CHARLES RIDOUT.
